UNITED STATES PATENT OFFICE

2,570,605

WATER SPRAYER

Miroslav Sigmund, Gosforth, England

Application September 24, 1948, Serial No. 51,060
In Great Britain October 1, 1947

1 Claim. (Cl. 299—69).

1

The present invention relates to improvements in water sprayers of the type comprising a rotatable nozzle, and a water diffusing or atomising element rotatably mounted on the nozzle, rotation of the diffusing element and the nozzle being effected by reaction pressure of the water jet emerging from the nozzle and impinging on the diffusing element.

In accordance with the invention a water sprayer is provided comprising a jet nozzle, a support therefor upon which said jet nozzle is capable of rotating, a rotary diffusing element mounted on the jet nozzle and rotatable thereon as a result of the reaction pressure between the water jet from the nozzle and said diffusing element, means driven by said rotary diffusing element for rotating the jet nozzle upon its support and means for reversing the direction of the rotation of the jet nozzle on the support under the drive of the diffusing element.

In accordance with a further feature of the invention means are provided whereby the direction of rotation of the jet nozzle may be reversed at predetermined variable points about its axis of rotation on the support so that water from the jet may be applied repeatedly over a selected sector of a circular area.

An embodiment of the invention is illustrated by way of example in the accompanying drawings in which Fig. 1 is a view in elevation and partly in section of a complete water-sprayer, Fig. 2 is a view in elevation and on a larger scale of a part of the transmission for imparting rotational movement to the sprayer nozzle. Fig. 3 is a view in elevation from the rear of Fig. 2, Fig. 4 is a view in side elevation and partly in section taken from the right hand side in Fig. 2 and Fig. 5 is a view in plan of the parts shown in Fig. 4.

Referring to Fig. 1 of the drawings, 1 is the jet nozzle formed by a tube or barrel having a suitable jet outlet aperture 2 at one end and connected at the other end to a curved hollow body 3 the lower end of which is formed as a cylindrical part 4 which is a rotatable fit in a ring 5 fixed at the upper end of a tube 6 fixed to and carried by a collar 7 and a tripod or equivalent stand 8. The tube 6 is of a form at its lower end 9 to be coupled to a water supply or hose pipe (not shown). An extension tube 10 is fitted within the lower cylindrical part 4 of the curved hollow body 3, said tube 10 extending into a suitably counter-bored portion of the fixed tube 6, a water-tight joint being provided between the tubes 6 and 10 by means of

2

a stuffing box 11. On the extension tube 10 below the cylindrical part 4 of the curved hollow body 3 is fixedly mounted a flanged ring 12 and between the ring 12 and the underside of a shoulder 13 on the interior of the fixed ring 5 at the upper end of tube 6 is mounted an anti-friction thrust bearing 14.

The barrel 1 towards its outlet end is preferably filled with a nest of parallel water tubes 15 to eliminate or reduce turbulence.

In operation, the barrel 1 is arranged at an upward inclination as shown in Fig. 1 and rotates about a general vertical axis on the stationary support, against the bearing 14.

Whilst a portable tripod or like stand 8 is shown in the drawings it will be understood that the barrel 1 may be mounted for rotation in bearings or any other convenient form of support e. g. at the upper end of a hydrant fixed to or forming part of a rigid water supply conduit.

The diffuser 16 is in the form of a spoked wheel having a plurality of inclined vanes 17 formed on its periphery, said diffuser 16 being mounted on a rotatable spindle 18 carried in bearings in a gear box 19 supported on the end of the barrel 1 and disposed so that the spindle 18 extends at an inclination to the axis of the barrel 1 e. g. approximately vertically as in the case illustrated.

As an example, the vanes 17 are inclined at an angle of about 45° to the general plane of the wheel 16 and are of uniform radial length and angular width and spacing with the exception of two or four vanes 17', equally distributed around the periphery, which are of approximately twice the angular width and radial length of the other vanes 17. The spacing between adjacent small vanes 17 may be a small fraction e. g. one fifth of the angular width of the small vanes, the spacing between the large vanes 17' and between the large vanes and adjacent small vanes being somewhat greater.

The spindle 18, carrying the diffuser 16, is provided with a helical groove 46 in which engages the end of a pin 47 fixed in the boss or hub of the diffuser 16, the arrangement being such that the diffuser is capable of limited up and down movement on the spindle 18 as determined by the movement of the pin 47 in the groove 46. The plane of rotation of the diffuser 16, when in its lowest position on the spindle 18, as determined by gravity, is such that all the vanes 17 and 17' project into the path of the water jet, issuing from the jet outlet 2 of nozzle 1, so that strong rotational impulses

are imparted through all the vanes 17 and 17' to the diffuser at starting, making for a rapid running up to speed. Due to its rotation the diffuser 16 is moved vertically upwards on the spindle 18 by virtue of the engagement of the pin 47 in the helical groove 46. This vertical movement partially withdraws the smaller vanes 17 from the water jet and thereafter rotation is maintained mainly by impingement of the water jet on the larger vanes 17', whilst the water jet is effectively broken up into a curtain. When the diffuser 16 reaches its uppermost position against a fixed stop 48 on the upper end of the spindle 18 it imparts rotation to the spindle 18.

Rotation of the diffuser 16 and the spindle 18 by the water jet is utilised to impart the rotation to the nozzle 1 about the vertical axis on its support.

For this purpose a worm (not shown) on the spindle 18 within the gear box 19 makes driving engagement with a worm wheel fixed on a spindle 20 projecting laterally from the gear box 19, and the end of said spindle carries a crank arm 21, the crank pin 22 of which is connected to one end of a rod 23 extending longitudinally of the jet nozzle 1. The other end of the rod 23 is pivotally connected with the upper end of a lever 24 mounted at its lower end for movement about one end of a spindle 25 extending through bearings in a gear box 26 carried by the curved hollow body 3 at the lower end of the jet nozzle 1.

The spindle 25 extends horizontally through the vertical plane containing the axis of the nozzle 1 and the lever 24 is of greater length than the crank arm 21, so that the lever 24 is caused to make to and fro rocking movements of given angular extent in a vertical plane about the axis of the spindle 25.

Upon the spindle 25, between the end of the gear box 26 and the lever 24 is keyed a ratchet wheel 27, and within the gear box 26 the spindle 25 carries a fixedly mounted worm 28 making meshing engagement through an aperture in the wall of the gear box 26 with the teeth 29 (Fig. 1) of a worm-ring 30 surrounding and fixed to the upper end of the fixed ring 5 forming a part of the stationary support.

Drive is imparted from the rocking lever 24 to the spindle 25 and therefore, through the reaction between the worm-ring 30 and the worm 28, to the nozzle 1 relative to its stationary support, through the co-operation of a pawl 31, carried by the lever 24, with the ratchet wheel 27.

The pawl 31 is formed as a three-armed body mounted to rock about a fixed pivot 32 on a lateral projection 33 intermediate the ends of the rocking lever 24, two of the arms 34 and 35 of the pawl 31 terminating in teeth each adapted to make one-way driving engagement with the teeth of ratchet wheel 27, the said teeth of the ratchet wheel 27 being of symmetrical form as shown. The pawl 31 is adapted to take either one of two alternative positions relative to the lever 24, in which one or the other but not both of the teeth on the two arms 34 and 35 is in engagement with the ratchet wheel and the arrangement is such that with the tooth on arm 34 of the pawl 31 in engagement with the ratchet wheel 27 step-by-step rotational movements are imparted to the ratchet wheel and therefore to the nozzle 1 in one direction during successive rocking movements of the lever 24 in one direction about the spindle 25, whilst with the tooth on the other arm 35 of the pawl 31 in engagement with the

ratchet wheel, step-by-step rotational movements are imparted to the ratchet wheel 27 and to the nozzle 1 but in the opposite direction, during successive movements of the lever 24 in the other direction about the spindle 25. The pawl 31 is retained in the selected one of its two alternative positions by the engagement of the end of a spring-loaded plunger 36 at one side or the other of a projection 37 on the edge of the pawl 31 (Fig. 2), the said plunger 36 being capable of yielding to an extent permitting the back of that tooth on arm 34 or 35 of the pawl 31, whichever is engaged with the ratchet wheel 27, to slide over the teeth of the ratchet wheel during the idle stroke of the pawl 31.

Means are provided to move the pawl from one of its two positions relative to the rocking lever 24, to the other to reverse the direction of rotation of the nozzle about the vertical axis on its support at each end of a movement of predetermined angular extent by the nozzle, so that the water spray may be deposited repeatedly over the same sector of a circular area.

For this purpose a setting member is provided in the form of a lever 38 fixedly mounted at one of its ends on a vertical spindle 39 carried in bearings at the end of the gear box 26 remote from the pawl 31. The free end of the lever 38 is furnished with a two-armed yoke 40 the arms 30 of which extend one on each side of the third and upwardly extending arm 41 of the pawl 31 but spaced therefrom, the width between the arms of the yoke 40 being such as to permit the pawl 31 normally to move in unison or substantially in unison with the lever 24, that is to say without the third arm 41 of the pawl 31 engaging said arms. The spindle 39 extends below the gear box 26 and at its lower end carries a crank arm 42 on the end of which is a downwardly extending pin 43.

Near the upper end of the fixed base support for the rotatable nozzle 1 is fixedly mounted a surrounding ring 44 carrying stop members 45 adjustable in position on the ring 44 about the vertical axis of rotation of the nozzle 1, these stop members 45 lying in the path of the above described downwardly extending pin 43.

The operation is as follows:

With the apparatus erected on its stationary support and tripod as in Fig. 1 and the water connection made at point 9, the water jet emerging from the outlet 2 from the nozzle 1 impinges upon the vanes 17 and 17' of the diffuser 16 so that the latter is caused to rotate with its spindle 18 on the nozzle 1. Rotation is imparted from the worm on the diffuser spindle 18 to the worm wheel on spindle 20 in the gear box 19 near the outlet end of the nozzle 1 and the crank-arm 21 rotated to reciprocate the rod 23 extending along the jet nozzle 1, to move the rocking lever 24 to and fro about the axis of the spindle 25. Movement is imparted from said lever 24 to the ratchet wheel 27 and the worm spindle 25 on which it is mounted, during the successive movements of the rocking lever 24 in one direction and according to the position of the three-armed pawl 31 relative to the lever, that is to say according to which of the teeth on the two arms 34 and 35 of the pawl 31 is in engagement with the ratchet wheel 27, the same tooth of the pawl 31 sliding over the ratchet wheel 27 during movements of the lever 24 in the reverse direction.

Thus the jet nozzle 1 is rotated on the fixed support formed by parts 5, 6, 7, 8, in a succession of steps in one direction through the engagement

or the worm 28 on the ratchet wheel spindle 25 in gear box 26, with the fixed worm ring 30 on the upper end of the support.

Rotational movement of the nozzle 1 in that direction continues until the downwardly extending vertical pin 43 on crank arm 42 at the lower end of spindle 39 makes engagement with one of the set adjustable stops 45 on the fixed ring 44 surrounding the fixed support. Thereafter, as the jet nozzle 1 is further moved, said pin 43 is held and the lever 38 mounted at the upper end of the spindle 39 supported by the gear box 26 moving with the jet nozzle 1 is caused to rock on the gear box 26 into position to change the relative positions of the arms of the yoke 40 and the third arm 41 of the pawl 31, and in such a manner that as movement of the rocking lever 24 continues the third arm 41 of the pawl body 31 engages a limb of the yoke 40 before the stroke of the lever 24 is completed and the pawl 31 is held and caused to rock relative to the lever 24 against the restraint of the spring-loaded plunger 36 to disengage the previously operative tooth on one of the arms 34 or 35 of the pawl 31 from the ratchet wheel 27 and engage the alternative tooth on the other arm 34 or 35 of the pawl 31 with the ratchet wheel 27, the spring-loaded plunger 36 engaging at the other side of the projection 37 on the pawl 31 to maintain the latter in the new position relative to the lever 24. Thereafter the jet nozzle 1 is rotated step-by-step but in the reversed direction until the other set stop 45 is engaged by the downwardly extending pin 43 to again move the lever 38 bearing the yoke 40. The direction of rotation of the nozzle 1 about the vertical axis is reversed each time the said pin 43 engages a stop member 45.

It will thus be seen that the diffused water jet from the nozzle may be caused to fall repeatedly upon the same selected sector of a circular area.

I claim:

A water sprayer, comprising a jet nozzle, a support therefor upon which said jet nozzle is capable of rotating, a rotary diffusing element mounted on the jet nozzle and rotatable by the jet of water from the nozzle, and means driven by said rotary diffusing element for rotating the jet nozzle upon

its support in either direction, said means including gearing between the rotatable jet nozzle and its support and a transmission between the diffusing element and said gearing comprising a ratchet wheel carried with and rotatable on the jet nozzle, a rocking member carried with the jet nozzle and rockable in a plane normal to the axis of the ratchet wheel, a double-ended pawl member pivoted on said rocking member for step-by-step driving cooperation with the ratchet wheel and means for moving said double-ended pawl between alternative positions on said rocking member, said means for moving the double-ended pawl member comprising a vertical spindle, bearings on the jet nozzle, said vertical spindle being supported in said bearings, a yoke fixedly mounted at the upper end of said vertical spindle and embracing a part of the double-ended pawl member with clearance, a crank fixedly mounted on said spindle and stop means connected with the stationary support for the rotary jet nozzle for engagement by the crank when the rotary nozzle reaches a selected point in its rotational movement on the support, to rotate said spindle and cause the said yoke to contact the double-ended pawl during a subsequent movement of said pawl with the rocking member to cause the double-ended pawl member to take its alternative position relative to the rocking member and reverse the direction of the step-by-step rotation of the jet nozzle on the support.

MIROSLAV SIGMUND.
